TRANSPARENT PAPER WEIGHT

Walter Hrolenok, 710 Oliver Ave., Fairmont, W. Va.

Filed Sept. 23, 1964, Ser. No. 81,845

Term of patent 14 years

(Cl. D74—12)

FIG.1

FIG. 1 is a top plan view of a transparent paper weight showing my new design.

FIG. 2 is a side elevational view of the paper weight.

FIG. 3 is a sectional view taken along line 3—3 of FIG. 1.

The design for a transparent paper weight is characterized by the particular contrasting pedestal having beads dispersed over its surface and embedded therein.

I claim:

The ornamental design for a transparent paper weight, substantially as shown and described.
